PAPER BOX

Harry L. Snyder, West Los Angeles, Calif.

Application September 6, 1943, Serial No. 501,380

3 Claims. (CL 229—16)

1

This invention relates to improvements in paper boxes.

Heretofore paper boxes have generally been constructed in conformity with two prevailing types, namely the tray type and the tube type. In the tray type wherein the paperboard, cardboard, or equivalent material is cut and scored to provide a bottom with sides foldable upwardly therefrom the boxes usually have the advantage of being capable of being shipped and stored in a conventional flat or knocked-down position. These boxes, however, are subject to the disadvantage that generally speaking they are weak against lateral pressures imposed on the sides. The tube type of box wherein the paperboard, cardboard, or equivalent material is formed into a tube that provides the sides of the box and which has flaps at the top and bottom which mutually cooperate to close the ends of the tube possess the advantage of having the sides adequately strong against expansive pressures, but the disadvantages of having the top and bottom relatively weak and the disadvantage that this type of box cannot be generally shipped or stored as conveniently as the tray type of box.

An object of the present invention is to provide an improved type of paper box wherein advantages of the tray type of box and of the tube type of box are combined enabling the boxes to be shipped or stored in a flat or knocked-down condition; enabling the boxes to be easily, conveniently, and quickly set up and providing a setup box structure which is adequately strong against lateral pressures on the sides of the box applied to the contained contents.

More specifically, an object of the invention is to provide a paper box consisting of a tray type blank which provides a bottom and upwardly foldable sides and which has a tube or band which cooperates with the upwardly foldable sides to reenforce them and adequately hold them in proper position against the lateral pressures applied thereto by the contained contents.

Another object of the invention is to provide a box having a cover, the box having closed side walls of double thickness between which flaps of the cover may be inserted and the box having end walls at the top of which there are ledges of adequate area covered or overlapped by the ends of the cover a sufficient distance so as to prevent the escape of the contents between the ends of the cover and the top of the end walls.

With the foregoing and other objects in view, which will be made manifest in the following detailed description and specifically pointed out

2

in the appended claims, reference is had to the accompanying drawings for an illustrative embodiment of the invention, wherein:

5 Fig. 1 is a top plan view of the blanks forming the improved box illustrating them in collapsed or knocked-down position;

Fig. 2 is a plan view of the blank that forms the cover for the improved box;

10 Fig. 3 is a perspective view illustrating the box in partially setup position;

Fig. 4 is a transverse section through the improved box in setup position, illustrating the cover in applied position thereon;

15 Fig. 5 is a partial view in longitudinal section illustrating the details of construction of one of the end walls;

Fig. 6 is a perspective view of a band and cover forming a part of a box of an alternative embodiment of the invention;

20 Fig. 7 is a perspective view of the body of the box with which the band shown in Fig. 6 may be utilized;

Fig. 8 is a plan view of a blank embodying another modified form of the invention; and

25 Fig. 9 is a perspective view illustrating the box made up from the blank shown in Fig. 6, and showing it in partially setup position.

Referring to the accompanying drawings wherein similar reference characters designate 30 similar parts throughout, the body of the improved box is formed of a blank of cardboard, paperboard, or equivalent material which is cut and scored so as to provide a bottom 10 with opposed side walls 11 and 12 foldable upwardly 35 from the sides of the bottom and opposed end walls 13 and 14 foldable upwardly from the ends of the bottom.

A pair of opposed scoring lines 15 and 16 define infolding sides 17 and 18 from the end walls 40 13 and 14, respectively. A tube type of band is provided having opposed sides 19 and 20 of substantially the same height as the side walls 11 and 12, but preferably slightly longer than the side walls. This band also has end walls 21 and

45 22 that are defined from the side walls such as by scoring lines 23 and which are substantially the same height as the end walls 13 and 14 are slightly longer than the end walls. The side walls 19 and 20 of the band or tube are preferably notched as at 24. This band may be formed of a single strip of cardboard, paperboard, or the like, the ends of which are connected together such as by a glue flap 25.

In the preferred form of construction, the side edges of the side walls 11 and 12 are notched as

indicated at 26, the depths of the notches being approximately equal to the thickness of the material utilized in forming the box. These notches are equal in length to narrow tongues 27 that are formed on the side edges of the in-folding sides 17 and 18. The tube or band that provides the sides 19 and 20 and the ends 21 and 22 is preferably, but not necessarily secured to one of the sides, such as the side 12. Thus, the side 20 of the tube or band may be stapled or glued 10 against the outer side of side 12.

A cover is provided of paperboard, cardboard, or equivalent material, which is cut and scored to provide a central cover panel 28 which is of substantially the same dimensions as the bottom 15 panel 10. Score lines 29 define side flaps 30 which are foldable downwardly therefrom.

The box embodying the present invention may be shipped or stored in the flat or knocked-down position shown in Fig. 1, wherein the sides 11 and 12, the ends 13 and 14 and the in-folding sides 17 and 18 are all in the plane of the bottom panel 10. The tube or band which has its side 20 secured against the outer face of side 12 is collapsed as shown in Fig. 1.

In setting up the box, side 11 is first folded upwardly with respect to the bottom panel 10. Side 12 is then folded upwardly and the tube or band shifted from its collapsed position to its expanded position. In erecting side 12 the tube or band is swung downwardly over the upwardly bent side 11 so that the side 19 of the tube or band is positioned against the outer face of side 11. The end walls 13 and 14 may then be bent upwardly and the in-folding sides 17 and 18 may then be swung over the tops of the ends 21 and 22 of the band. In so doing, the material forming the ends of the blank is folded on both score lines 15 and 16 so that the space therebetween forms a ledge indicated at 31 of considerable area at the top of each end of the box. On folding the in-folding sides 17 and 18 downwardly the tongues 27 are caused to enter the recesses 26 at the ends of the sides 11 and 12 so as to interlock therewith and thus retain the in-folding sides in position.

The cover may then have its side flaps 30 folded downwardly with respect to the cover panel 28 and these side flaps can then be inserted between side 12 and side 20 and side 11 and side 19 respectively. The notches 24 in the sides 19 and 20 facilitate flexing the sides 11 and 12 inwardly so as to space them from the tube or band sufficiently to facilitate the entry of the side flaps. The attaching means, such as glue or staples when employed that attaches side 20 to side 12, is preferably so positioned with relation to the corners of the side flaps 30 as not to interfere with the insertion of these flaps.

While it is desirable to have the tube or band fastened to side 12 in order to keep the two blanks of the box permanently associated this is not necessary as in some instances the body of the boxes may be shipped or stored in the form of two completely detached blanks that can be assembled together in substantially the same manner as above described.

As will be noted from an inspection of Fig. 5, the ledge 31 between adjacent score lines 15 and 16 is overlapped by the ends of the cover panel 28 to a considerable extent. Consequently, leakage of the contents of the box between the cover and the ends of the box is effectively prevented regardless of how the box may be positioned in handling.

The above described box possesses most of the advantages of the tray type of box in that it may be shipped or stored in a flat condition and easily and quickly set up. It is advantageous over the conventional tray type of box in that the sides are effectively reenforced against outward spreading by the band which encircles sides 11 and 12. The ends of the box which are foldable over the ends of the band are also effectively reenforced by the band. The improved box is thus of a quite sturdy construction when set up, there being double thicknesses at the side walls and three thicknesses at each end. When the cover is applied the side flaps 30 thereof which are inserted between sides 12 and 20 and 11 and 19 form the third thickness at the sides of the box.

In Figs. 6 and 7 there is illustrated a modified form of the invention wherein the band and body of the box may be shipped and stored separately or independently. In this form of construction the band comprises a back wall 35 equipped with integral ends 36 and 37 the end 37 having a front wall 38 integral therewith and connected to the end 36, such as by a glue flap 39. The cover 40 equipped with a sealing flap 41 is hingedly connected to the back wall as on the fold line 42.

The body of the box illustrated in Fig. 7 comprises a bottom 43 having sides 44 and 45 foldable upwardly therefrom. The ends of the bottom have end walls 46 and 47 foldable upwardly 30 from the bottom and these ends have infolding sides 48 and 49 defined therefrom by spaced fold lines 50 and 51.

In assembling the box of this type of construction the sides 44 and 45 are first bent upwardly 35 from the bottom. The band is opened into direct angular position shown and is slipped or telescoped over these upstanding sides. The ends 46 and 47 are then bent upwardly against the outer faces of the ends 36 and 37 and the infolding sides 48 and 49 are then folded inwardly against the inner faces of the ends 36 and 37. The spaced fold lines 50 and 51 provide the ledges at the ends of the box having the same function as above described.

The sealing flap 41 is receivable between the front wall 45 of the box and the front wall 38 of the band. In this form of construction it will be appreciated that the two side walls of the box are of double thickness, the thicknesses being provided by the sides 35 and 44 at the back and 38 and 45 at the front. The ends of the box are of three thicknesses.

In Figs. 8 and 9 still a further form of the construction is disclosed wherein the box may be cut and scored from a single blank. In that form of construction the blank provides a bottom 50 at the front and back of which there are upwardly foldable sides 51 and 52 respectively. At the ends of the bottom 50 there are upwardly foldable ends 53 and 54 which are equipped with infolding sides 55 and 56 which are defined from the ends by the parallel fold lines 57. The ends of the rear side 52 have integral therewith ends 58 and 59 and a forward side 60 is integral with the end 59. The free end edge of this forward side is attachable to end 58 such as by glue flap 61.

A cover 62 equipped with a sealing flap 63 is integral with the top edge of side 52. In this form of construction the blank may be shipped in completely open position and a short time prior to use glue flap 61 attached to the end of the forward side 60 of the band. If desired, 70 however, glue flap 61 may be attached to forward

side 60 at the time the box is initially constructed and the blank 11 with the band collapsed as shown in Fig. 1. In setting up the box the forward side 51 is first bent upwardly and the band positioned thereover so as to encircle it as shown in Fig. 9. Thereafter the ends 53 and 54 may be bent upwardly against the outer faces of ends 58 and 59 of the band and finally the infolding sides 55 and 56 positioned inside of the box.

The improved box may be advantageously used for many purposes. It has been primarily designed for use as a shoe box but may be used for many purposes desired. When utilized to hold finely divided substances the broad engagement between the ledges 31 and the cover effectively prevents leakage between the cover and the ends of the box. In the construction shown in Figs. 1 to 5 inclusive, the cover may be opened from either side by merely extracting the sealing flap 30 this side and leaving the other sealing flap in position. The cover may then hinge relatively to the sealing flap that is left in position. It is not essential that the infolding sides 17 and 18 be equipped with tongues 27 or that the sides 11 and 12 be equipped with complementary recesses 26. Thus in the constructions shown in Figs. 6 to 9, inclusive, these tongues and recesses are illustrated as omitted. The tongues and recesses corresponding to these tongues and recesses may be used on the constructions shown in Figs. 6 to 9 inclusive if desired.

Various changes may be made in the details of construction without departing from the spirit and scope of the invention as defined in the appended claims, wherein I claim:

1. A paper box having a bottom, sides foldable upwardly therefrom, means providing a band extending from one side to encircle the other, ends foldable upwardly from the bottom against the outer faces of the ends of the band, and

40

infolding sides attached to the ends adapted to be positioned against the inner faces of the ends of the band and against at least one side positioned against the interior face of the band, said infolding sides being defined from said ends by spaced parallel folded lines to provide ledges at the tops of the ends of the box, and a cover for the box adapted to engage said ledges at the ends of the box.

2. A paper box comprising means providing an encircling band having opposed sides and ends, and a bottom having at least one side foldable upwardly therefrom adapted to be positioned against the inner face of one side of the band, said bottom having outer ends foldable upwardly therefrom adapted to be positioned against the outer faces of the ends of the band, and infolding ends foldable from said outer ends adapted to be positioned against the inner faces of the ends of the band and against said side foldable upwardly from the bottom positioned against the inner face of one side of the band.

3. A paper box comprising means providing an encircling band having opposed sides and ends, and a bottom having at least one side foldable upwardly therefrom adapted to be positioned against the inner face of one side of the band, said bottom having outer ends foldable upwardly therefrom adapted to be positioned against the outer faces of the ends of the band, and infolding ends foldable from said outer ends adapted to be positioned against the inner faces of the ends of the band and against said side foldable upwardly from the bottom and positioned against the inner face of one side of the band, said infolding ends being defined from said outer ends by spaced parallel fold lines so that the material between the fold lines forms ledges projecting inwardly from the tops of said outer ends of the box.

HARRY L. SNYDER.
